UNITED STATES PATENT OFFICE.

CECIL L. SAUNDERS, OF ITHACA, NEW YORK.

CLEANING DEVICE.

1,270,216.

Specification of Letters Patent. Patented June 18, 1918.

Application filed April 8, 1918. Serial No. 227,301.

To all whom it may concern:

Be it known that I, CECIL L. SAUNDERS, a citizen of the United States, residing at Ithaca, in the county of Tompkins and State 5 of New York, have invented certain new and useful Improvements in Cleaning Devices, of which the following is a specification.

My invention relates in general to an apparatus for cleaning such materials as cotton, grain, wool, or other fibrous materials and particularly to a cotton-ginning device in which the separation of seeds from the fibers is effected by a combination of pneumatic and mechanical devices and is an improvement on the type of machine shown in U. S. Patent No. 849,141, granted to Story B. Ladd April 2, 1907, and my own prior Patent No. 1,075,304, patented October 7, 20 1913.

In both these prior patents means are described for pneumatically holding the fiber onto a moving perforated surface, the seeds being removed by coming into contact with 25 knives or blades.

My present invention relates to improved means for removing the seeds and comprises a belt or like device or devices for bringing the cotton or other material to be cleaned 30 into proximity with the moving suction surface, such as a perforated roll or cylinder, in combination with a series of edges, which may take the form of a series of knife edges or be the edges of holes in a perforated 35 plate, the fibers being drawn over the edges by the suction, while the seeds are held back by the edges and pushed or drawn along by the moving belt over the knives or perforated plate and thus removed from the 40 field of the suction and discharged from the machine.

My invention has for further object to provide means for removing the fiber from the perforated suction surface in an evenly 45 laid and untangled condition; to remove mites and other undesirable material; and to provide other improvements in details of construction, as will more fully appear from the accompanying specification and claims.

50 Referring to the drawings—

Figure 1 is a sectional elevation of a portion of the machine;

Fig. 2 is a detail view of one form of stripping-plate;

Fig. 3 is a cross-section showing the relative position of the suction surface, another form of stripping-plate, and the belt;

Fig. 4 is a detail view of the corrugated stripping-plate, shown in Fig. 3;

Fig. 5 is a sectional elevation of a modified form of machine;

Fig. 6 is a detail view on an enlarged scale of the stripping-plate, and ginning-blade used in the machine of Fig. 5;

Fig. 7 is a modification in which the belt 65 and suction surface move in relatively opposite directions;

Fig. 8 is a side elevation of Fig. 7, the belt being removed; and

Fig. 9 shows another form of stripping- 70 plate.

Referring to Fig. 1, 1 is the perforated moving surface, which in this particular embodiment of the machine, takes the shape of a suction and blast cylinder or roller, which 75 may be constructed as shown in the prior patents referred to. 2 is a perforated metal plate secured at each end and having perforations therein of less size than the cotton-seed, or the distance between the seeds. The 80 plate is preferably made of sheet-steel and has a portion thereof bent to conform accurately to the curvature of the suction cylinder 1. This plate as shown is permanently secured in place, but may be so mounted as 85 to have a reciprocating or rotary motion. 4 is an endless belt passing around rollers 5, 6, and driven in the direction indicated by the arrows and at a linear velocity less than that of the perforated roller 1. Idler 90 rolls 7, 7 may be used to hold the inner run of the belt into as close relation to the stripping-plate 2 as may be necessary. 3 is the hopper through which the cotton to be ginned is fed downwardly into the machine. 95 52 is a rotary comb to assist in the delivery of the cotton.

As shown in Fig. 2, the perforated plate may be provided with long narrow slots 8; or as shown in Figs. 3 and 4, this perforated 100 stripping-plate 20 may be corrugated, the belt 40 having cords or ridges extending into the corrugations. This belt may be made of fiber matting which has a rough

or hairy surface to which the fiber attached to partly cleaned seeds will adhere, so that such seeds will be carried back by the belt, from which they may be removed by the rotary brush 53 or any other suitable means, and be again submitted to the ginning operation; or the belt may be made of card clothing such as is used in carding machines; or may be of porpoise hide, or of smoother material, such as leather, metal, etc.

In operation, the cotton to be cleaned is fed into the hopper 3, and carried down between the belt and stripping-plate. The suction from the cylinder 1, acting through the perforations of the stripping-plate, sucks away the dust and dirt through the perforations and pulls off the fiber from the seeds, the fibers being held onto the cylinder 1 by the suction. The fibers pulled off the seed and held onto the cylinder by the suction, are carried along between the cylinder 1 and the stripping-plate and are removed from the cylinder by any suitable means, such as a doffing roll 9, which delivers the fiber to an endless belt 10; or may be blown off by the blast from the blast chamber.

The seeds held back by the edges of the perforations in the plate 2 are carried along by the belt 4, the seeds from which the lint has been thoroughly removed dropping out, as shown by the arrow C, while the seeds from which all the lint may not have been removed, adhere to the rough or hairy surface of the belt and are carried around by it until they reach the brush 53, by which they are delivered to the incoming cotton to be again treated.

In the modified form of machine shown in Fig. 5, the parts corresponding to like parts in Fig. 1 are marked with a corresponding number having a prime mark. In this modified machine, the stripping-plate 2' extends over a portion of the suction cylinder but in the same relation thereto as heretofore described. Either of the forms of stripping-plate above referred to may be used.

12 is a ginning-blade having teeth 13, curved to fit the contour of the roller, and is mounted beneath the plate 2', this blade being either stationary or provided with suitable reciprocal means. 14 is a seed screen through which the seeds drop into a seed receptacle 15, which is provided with any suitable delivery mechanism, such as an endless conveyor 16. As indicated in dotted lines, the rollers 5' and 6' may be mounted so as to be adjusted with reference to the suction cylinder. 17 is a mote board for removing motes and other material from the ginned cotton, and 18 is a combing device for removing the ginned lint from the cylinder. This comber may be arranged to reciprocate in the same manner as the comber in a carding-machine, thus removing any twist from the ginned fiber.

In both the forms of machine described, the removal of the cleaned fiber from the suction portion of the cylinder is effected by mechanical means, the blast serving mainly as a means for cleaning out the perforations; 70 although the blast may, as in the prior patents, be used wholly or in part as the means for removing the fibrous material from the suction cylinder.

The operation of the form of machine 75 shown in Fig. 5 is substantially like that shown in Fig. 1. The ginned fiber is carried around by the suction cylinder and removed by the comber 18, while the seeds separated from the fiber by the action of the stripping-plate 2' and ginning-blade 12 fall into the receptacle 15.

In either form of machine, the speed of the belt 4 and 4' must be carefully adjusted to that of the suction cylinder, in accordance 85 with the material being treated. In practice, I have found that the ratio of belt speed to lineal velocity of the cylinder periphery should be about 1 to 36, although any other suitable ratio may be used.

90 In Fig. 6 is shown a special form of stripping-plate in which the openings, while not large enough to permit passage of the seeds, are of such area that the seeds may project therethrough and come into actual contact with the suction cylinder, thereby permitting a particularly effective action of the suction.

In Fig. 7 is shown a machine substantially like that shown in Fig. 1, except that the pressure belt 4" moves in a contrary direction to that of the suction surface or cylinder 1. In this figure, I have shown the hopper board 60 as provided with hole-opening or spreading teeth 61, arranged as shown in Fig. 8, in which figure is shown still another 100 form of stripping-plate having inclined slots 8" in staggered arrangement. In this form of machine the cotton to be cleaned is fed into the hopper and as it passes downward, is opened out by the pins 61 and thence onto the perforated plate. As the belt forces the material along over the edges of the perforations (or the edges of the series of knives), the fiber is sucked away from the seeds at each edge. The material is thus 110 successively presented to clear portions of the suction cylinder.

115 As will be apparent, the cleaning edges which serve to separate the seeds from the fiber or lint may be the edges of the openings 120 in a perforated plate or wire screen or any other series of openings. Thus in Fig. 9, I have shown a series of knives having corrugated edges bent to correspond to the shape of the suction cylinder, and arranged in 125 spiral lines, the edges of the knives being spaced apart a proper distance from each other and from the cylinder surface to prevent passage of the seeds thereunder, while the lint or fiber may readily be carried along 130

by the cylinder while held against its surface by the suction.

It will be evident that the various elements of my machine may be modified without departure from my invention. Thus a rotating or reciprocating perforated plate, provided with suction chambers might be substituted for the revolving perforated suction cylinder; or a series of rollers might be substituted for the endless pressure belts 4, 4'; and other mechanically equivalent devices for feeding unginned cotton to and removing the ginned cotton from the suction cylinders, may be used.

15 While my machine is particularly designed for ginning cotton, the principle of operation by which one ingredient is pneumatically held, while a second ingredient is separated therefrom, is manifestly capable 20 of application in various other relations.

I claim:—

1. The combination with a moving perforated surface and means for producing suction therethrough, of a perforated stripping-plate arranged in proximity and conforming to said perforated surface, and means moving relatively to the perforated surface for pressing the material to be cleaned against the perforated plate.

30 2. The combination with a rotatable perforated cylinder and means for producing suction therethrough, of a perforated stripping-plate arranged in proximity to and conforming to the contour of said cylinder, 35 and a belt constructed and arranged to move relatively to the perforated surface for pressing the material to be cleaned against the perforated stripping-plate.

3. The combination with a rotatable perforated cylinder and means for producing suction therethrough, of a perforated stripping-plate arranged in proximity to and conforming to the contour of said cylinder, and a belt having a surface to which fibers 40 adhere and constructed and arranged to move relatively to the perforated surface for pressing the material to be cleaned against the perforated stripping-plate.

4. The combination with a moving perforated surface and means for producing suction therethrough, of a perforated stripping-plate arranged in proximity and conforming to said perforated surface, means moving relatively to the perforated surface 55 for pressing the material to be cleaned against the perforated plate, and means for removing the cleaned material from the suction surface.

5. The combination with a rotatable perforated cylinder and means for producing suction therethrough, of a perforated plate having a portion arranged in proximity to and conforming to the contour of the rotatable cylinder, a movable pressure device 60 for pressing the material to be cleaned

against the perforated plate, and a ginning-blade located below the perforated plate.

6. The combination with a moving perforated surface and means for producing suction therethrough, of a device having 70 spaced edges arranged in proximity to the perforated surface, and means moving relatively to the perforated surface constructed and arranged to press the material to be cleaned against the spaced-edge device and 75 to remove therefrom the material held back by the edges.

7. In a pneumatic cotton-gin, the combination with a moving perforated surface and means for producing suction therethrough, 80 of a device having spaced edges arranged in proximity to the perforated surface, means moving relatively to the perforated surface constructed and arranged to press the cotton to be ginned against the spaced-edge device 85 and to remove therefrom the seeds held back by the edges.

8. In a pneumatic cotton-gin, the combination with a moving perforated surface and means for producing suction therethrough, 90 of a device having spaced edges arranged in proximity to the perforated surface, a belt moving relatively to the perforated surface constructed and arranged to press the cotton to be ginned against the spaced-edge device 95 and to remove therefrom the seeds held back by the edges.

9. In a pneumatic cotton-gin, the combination with a moving perforated surface and means for producing suction therethrough, 100 of a device having spaced edges arranged in proximity to the perforated surface, a belt moving relatively to the perforated surface constructed and arranged to press the cotton to be ginned against the spaced-edge device 105 and to remove therefrom the seeds held back by the edges, and means for delivering the cotton to the space between the belt and spaced-edge device.

10. The combination with a moving perforated surface and means for producing suction therethrough, of a perforated stripping-plate arranged in proximity and conforming to said perforated surface, means moving relatively to the perforated surface 110 for pressing the material to be cleaned against the perforated plate, and means for mechanically removing the lint cotton from the perforated surface.

11. The combination with a rotatable perforated cylinder and means for producing suction therethrough, of a perforated stripping-plate arranged in proximity to and conforming to the contour of said cylinder, a belt constructed and arranged to move 125 relatively to the perforated surface for pressing the material to be cleaned against the perforated stripping-plate, and means for mechanically removing the lint cotton from the perforated surface.

12. The combination with a rotatable perforated cylinder and means for producing suction therethrough, of a perforated stripping-plate arranged in proximity to and conforming to the contour of said cylinder, a belt having a surface to which fibers adhere and constructed and arranged to move

relatively to the perforated surface for pressing the material to be cleaned against the perforated stripping-plate, and means for 10 mechanically removing the lint cotton from the perforated surface.

In testimony whereof I affix my signature.
CECIL L. SAUNDERS.
